UNITED STATES PATENT OFFICE

101,607

DESIGN FOR A VACUUM CASTING APPARATUS

Michael Annick, Scranton, Pa., assignor, by
mesne assignments, to Wesel Manufacturing
Company, a corporation of Pennsylvania

Application January 24, 1934, Serial No. 50,499

Term of patent 14 years

To all whom it may concern:

Be it known that I, Michael Annick, a citizen of the United States, residing at 617 Harrison Avenue, in the city of Scranton, county of Lackawanna, State of Pennsylvania, have invented a new, original, and ornamental Design for a Vacuum Casting Apparatus, of which the following is a specification, reference being had to the accompanying drawing, forming part thereof.

Figure 1 is a perspective view of a vacuum casting apparatus, showing my new design.

Figure 2 is a perspective view thereof in open position and taken from a different angle.

I claim:

The ornamental design for a vacuum casting apparatus, as shown.

MICHAEL ANNICK.
